POWER-OPERATED ERASER FOR ELECTRIC
TYPEWRITERS

Martha M. Alden, Tulsa, Okla.

Application September 2, 1949, Serial No. 113,889

3 Claims. (Cl. 197—181)

1

My invention relates to a power operated erasing attachment for electric typewriters.

A primary object of my invention is to provide an erasing attachment for electric typewriters, operated from the electric motor of the typewriter, and mounted upon the typewriter in a convenient and accessible position.

A further object is to provide an erasing attachment of the above-mentioned type, including mechanism operated by the removal of the eraser from a support for detachably engaging the armature shaft of the typewriter motor to drive the eraser.

A further object is to provide a device of the above-mentioned character which is highly simplified, durable, and quite inexpensive to manufacture.

Other objects and advantages of my invention will be apparent during the course of the following description.

In the accompanying drawings, forming a part of this application, and in which like numerals are employed to designate like parts throughout the same,

Figure 1 is a side elevation of an electric typewriter equipped with the power-operated erasing attachment embodying my invention.

Figure 2 is an enlarged fragmentary horizontal section through a portion of the typewriter casing and showing mechanism forming part of my attachment, and

Figure 3 is a fragmentary vertical section, taken on line 3—3 of Figure 2.

In the drawings, where for the purpose of illustration is shown a preferred embodiment of my invention, the numeral 10 designates generally an electric typewriter of conventional construction, and including the usual platen 11 and keys 12. The typewriter further comprises a housing or casing 13, having a bottom 14 and a vertical side 15. The typewriter is provided with a drive motor 16, fixedly secured to the bottom 14, inwardly of and near the side 15 of the casing, and having its armature shaft 17 extending parallel to the side 15 and toward the front of the typewriter. A reduction gear box and power takeoff 18 for the typewriter drive is provided forwardly of the motor 16, and this reduction gear box has a horizontal shaft 19 connected by a coupling 20 with the armature shaft 17. The shaft 19 extends horizontally forwardly of the reduction gear box 18 and carries a clutch plate 21, having secured thereto a female conical clutch element 22 of hard rubber, or the like. When the typewriter master switch, not shown, is on, the

2

motor armature shaft 17 and reduction gear box shaft 19 rotate continuously. All of the construction thus far described is conventional and well-known.

5 A large rectangular opening 23 is provided in the side 15 of the typewriter casing, and a removable rectangular cover 24 is detachably rigidly secured to the side 15, adjacent to the opening 23, by any suitable means. The cover 24 includes 10 an outer vertical side 25, upon which is rigidly mounted a horizontal inwardly extending arm or bracket 26, which projects into the typewriter casing, as shown, and carries a bearing 27, in axial alignment with the shafts 17 and 19. 15 Journalled within the bearing 27 for rotation is a horizontal shaft 28, provided at its rear end with axial splines 29, engaging slidably within axial grooves 30, formed internally in a head 31 of a forwardly and rearwardly shiftable clutch shaft 20 32. The clutch shaft 32 has a fixed collar or shoulder 33 secured to it, rearwardly of the head 31 and held against axial movement. This shoulder 33 may be a ball bearing, having its inner race tightly pressed upon the clutch shaft 32 25 and its outer race freely rotatable. Secured to the rear end of the clutch shaft 32 for rotation therewith is a clutch plate 34, carrying a male conical clutch element 35 formed of hard rubber, or the like. The clutch shaft 32 is supported by 30 the shaft 28 and is shiftable axially in both directions upon the splines 29 for engaging and disengaging the clutch elements 22 and 35.

An inwardly extending upwardly inclined support bracket 36 is rigidly secured to the cover 24 near its longitudinal center, and generally opposite the shoulder or ball bearing 33. The top of this support bracket 36 is arranged substantially at the elevation of the horizontal shaft 32, and pivotally mounted upon the top of the support bracket 36 for horizontal swinging movement is a clutch actuating lever or plate 37, which extends inwardly beyond the inner end of the support bracket and is provided with a head 38 having a recess or notch 39 in its inner end, for receiving the outer race of the bearing or shoulder 33. The clutch actuating lever 37 extends outwardly through a slot 40, formed in the side 25 of the cover. Outwardly of the cover 24, an upstanding vertical bar or plate 41 is rigidly secured at its lower end to the lever 37, and projects above the lever to an elevation near and above the top of the cover 24, Figure 1. Secured to the top of the bar 41 is a spring clip or holder 42, for releasably holding in the vertical position the housing or 55 casing 43 of a rotary type power driven eraser

having a removable rotary rubber erasing tip 44. The rotary erasing tip 44 is driven by a flexible shaft 45, extending through forward end of the typewriter, as shown at 46, and operatively connected with the shaft 28 by a suitable coupling 47.

A fixed horizontal web 48 is secured within the cover 24, at the elevation of the lever 37, and a retractile coil spring 49 has its opposite ends connected in apertures 50 and 51 formed in the lever 37 and web 48, respectively. The aperture 50 is disposed longitudinally inwardly of a pivot screw 52, which serves to pivotally connect the lever 37 and support bracket 36. The spring 49 extends diagonally outwardly upon the right side of the lever 37, Figure 2, and tends to bias the head 38 of the lever to the right for engaging the clutch element 35 within the element 22. The slot 40 has a downwardly offset portion 40' at its right end, Figure 2, within which the lever 37 may engage when the clutch elements are disengaged, as shown in Figure 2, so that the spring 49 will not be able to swing the head 38 to the right. The lever 37 is somewhat resilient, and when its outer end is elevated slightly, it will enter the upper portion of the slot 40 at the left, Figure 2, and the outer end of the lever will swing to the left, Figure 2, under the influence of the spring 49, swinging the head 38 to the right for engaging the clutch elements.

In use, the clutch elements 22 and 35 remain normally disengaged and the clutch shaft 32 will not rotate with the constantly rotating shaft 19. The eraser casing 43 remains normally in a vertical position adjacent to the right side 15 of the typewriter casing and held within the resilient spring clip 42. When it is desired to use the power-operated eraser the typist grasps the casing 43 which serves as a handle and disengages the same from the clutch 42. When doing this, the typist elevates the free end of the lever 37 slightly so it may enter the upper portion of the slot 40 and be swung to the left, Figure 2. The spring 49 will cause this swinging movement as soon as the outer end of the lever 37 is elevated slightly, and the swinging will therefore be automatic. When it occurs, the head 38 swings to the right and the recess 39 engages the outer race of the ball bearing 33 and shifts the clutch shaft 32 axially to the right so that the clutch element 35 will engage within the element 22. When this occurs, the clutch shaft 32 will rotate with the shaft 19, and the shaft 28 will also be driven for driving the flexible drive shaft 45. The shaft 45 will in turn rotate the eraser tip 44, and the implement may be employed for erasing.

When the erasing operation is completed, the typist merely returns the casing 43 to the clip 42, pressing the lever 37 rearwardly or to the right, Figure 2, where it will enter the downwardly offset portion 40' of the slot 40. The head 38 will accordingly be swung to the left, Figure 2, for disengaging the clutch elements and the rotary erasing tip 44 will stop. The engagement of the lever 37 in the slot portion 40' prevents the lever from again swinging to engage the clutch elements, until the eraser casing 43 is again removed.

It is thus seen that I have provided a power-operated erasing attachment which receives its power from the constantly rotating motor shaft of the electric typewriter, and I have provided the novel mechanism described above for actuating the clutch elements which drive the attach-

ment. The attachment is very simple, durable and inexpensive to manufacture.

It is to be understood that the form of my invention herewith shown and described is to be taken as a preferred example of the same, and that various changes in shape, size and arrangement of parts may be resorted to, without departing from the spirit of the invention, or the scope of the subjoined claims.

Having thus described my invention, I claim:

1. An erasing attachment for an electric typewriter having a drive motor including a drive shaft, said attachment comprising a housing mounted on the typewriter casing, a driven shaft journaled for rotation within the housing, said driven shaft being axially movable and in axial alignment with the drive shaft, clutch elements cooperatively carried by the adjoining ends of the shafts, a rotary eraser drivingly connected to said driven shaft, an operating lever pivotally mounted in the housing and said housing having a slot formed in one wall thereof through which the lever is extended, means connecting the lever to the driven shaft for shifting said shaft axially to engage the clutch elements, resilient means actuating said lever in its movement effecting engagement of the clutch elements, a holder on the exterior end of the lever, said eraser being detachably mountable on said holder and said slot having a recessed end for lockingly receiving the lever and retaining it in an inoperative position, said lever being held in said recess by the weight of the eraser in the holder.

2. An erasing attachment for an electric typewriter having a casing and a drive motor including a drive shaft, comprising a driven shaft journaled for rotation within the casing, said driven shaft being movable toward and away from the drive shaft, clutch elements co-operatively carried by the respective shafts, a rotary eraser drivingly connected to the driven shaft, an operating lever pivotally mounted in the casing and said casing having a slot formed in one wall thereof through which the lever is extended, means connecting the lever to the driven shaft for shifting the driven shaft toward the drive shaft to engage the clutch elements, resilient means actuating said lever in its movement effecting engagement of the clutch elements, and a holder on the exterior end of the lever, said eraser being detachably mountable on said holder and said slot having a recessed end for lockingly receiving the lever and retaining it in an inoperative position, said lever being held in the recessed end of the slot by the weight of the eraser in the holder.

3. An erasing attachment for an electric typewriter having a casing and a drive motor including a drive shaft, said attachment comprising a housing mounted on the casing, a driven shaft journaled for rotation within the casing, said driven shaft being axially movable and in axial alignment with the drive shaft, clutch elements co-operatively carried by the adjoining ends of the shaft, a rotary eraser drivingly connected to said driven shaft, an operating lever pivoted intermediate its ends within the casing for swinging movement in a horizontal plane, said housing having a slot formed in one wall thereof through which the lever is extended, means connecting the lever to the driven shaft at one end of the lever for shifting said shaft axially to engage the clutch elements responsive to swinging movement of the lever in one direction, a spring connected at its opposite ends to the lever

and housing, respectively, and arranged to normally exert pressure against the lever tending to swing the lever in said direction to engage the clutch elements, and a holder on the exterior end of the lever, said eraser being detachably mountable on said holder and said slot having a downwardly offset portion at one end thereof for lockingly receiving the lever and releasably engaging the same against movement in said direction, said lever being held in said downwardly offset portion by the weight of the eraser in the holder.
